Filed Apr. 13, 1973, Ser. No. 350,897

Term of patent 3½ years

Int. Cl. D19—07

U.S. Cl. D19—62

FIG. 1

FIG. 2

FIG. 3

FIG. 4

FIG. 1 is a top plan of a lacing and tying educational device showing my new design;

FIG. 2 is a side elevational view thereof, the side opposite being substantially identical;

FIG. 3 is a left-end elevational view thereof; and

FIG. 4 is a right-end elevational view thereof.

The lace portions of the figures are lined to indicate color.

The characteristic feature of my design lies in the outward continuous curve of the front of the shoe flaps and the termination of the rear of the flaps adjacent the forward end of the representation of the shoe opening.

I claim:

The ornamental design for a lacing and tying educational device, as shown and described.
